UNITED STATES PATENT OFFICE.

THOMAS S. TONGUE, OF BIRMINGHAM, COUNTY OF WARWICK, ENGLAND.

DRIVING MECHANISM FOR SEWING AND OTHER MACHINES.

SPECIFICATION forming part of Letters Patent No. 253,240, dated February 7, 1882.

Application filed December 20, 1881. (No model.) Patented in England October 24, 1878.

To all whom it may concern:

Be it known that I, THOMAS SKELDING TONGUE, of Birmingham, in the county of Warwick, in the United Kingdom of Great Britain, have invented certain new and useful Improvements in Driving Mechanism for Sewing and other Machines; and I do hereby declare that the following is a full, clear, and exact description of the invention, which will enable others skilled in the art to which it appertains to make and use the same, reference being had to the accompanying drawings, which form a part of this specification.

This invention relates to certain improvements in the driving mechanism for sewing and other machines, and has for its object to so construct and arrange the fly-wheel and the driving-wheel, that the latter can be made either fast or loose upon its shaft at the will of the operator, whereby he will be enabled to wind cotton for shuttles or on spools without driving the machine.

A further object of my invention is to improve the arrangement of treadles, as hereinabove fully set forth.

In the drawings, Figure 1 illustrates the application of my improvement to a sewing-machine stand or frame. Fig. 2 is a perspective view of the driving-wheel. Fig. 3 is a view of the spring-ring and wedge, and Fig. 4 represents the fly-wheel, and Fig. 5 represents a modification.

A indicates the fulcrum-bar of the two treadles B B, which bar I arrange at the front of the frame or stand C, the treadles leading therefrom rearward or away from the operator.

D indicates a bar connecting the fulcrum-bar with the rear tie-rod, E; and F represents the standard, which is secured upon bar D; and on which the vibratory beam G is pivoted. This vibratory beam connects with the rear ends of the treadles by means of links H, one of the said treadles being connected by a connecting-rod, I, with a crank upon the driving-shaft K.

On the driving-shaft are mounted the loose driving-wheel L and the fly-wheel M, which is rigid upon said shaft. The fly-wheel, or, as herein shown, the driving-wheel, is recessed, as in Fig. 2, and within a circular channel in said recess is arranged an iron or steel spring-ring, N, made square in cross-section, and having a

slot, O, which receives one end of a wedge, P. The hub Q of the fly-wheel closes the recess of the driving-wheel, and upon said hub, at different distances from its center, are the two pins R R, arranged eccentrically, as shown in Fig. 4. These pins project within the recess of the driving-wheel and are employed to act upon the wedge. When the fly-wheel is revolved in one direction the outer pin, acting upon the wedge at a point near the connection of the wedge with the ring, will cause the ring to turn in its circular bed or channel; but during a reverse movement of the fly-wheel the inner pin, striking the inner end of the wedge, will move or turn the same from the radial position shown in Fig. 2, and hence spring the ring so as to cause it to bind against the walls of its channel, and thus cause the driving-wheel to rotate in unison with the fly-wheel and the driving-shaft. The driving-wheel being thus either fast or loose upon its shaft at the will of the operator, he is enabled to wind the cotton for shuttles or on spools without driving the machine.

By the application of the above-described driving mechanism to such and other similar purposes or uses the action and driving are rendered much less laborious than heretofore, the beam being situated with its treadles at the rear of the machine, in lieu of at the front, the latter being too direct a motion and tiring and difficult to work; but by transferring the beam to the position shown the machine can be operated with great ease.

In the modification, Fig. 5, the inner and fixed wheel, S, has wedge-shaped recesses in its periphery, and the outer wheel, S', is recessed to receive the driving-wheel and formed with an annular wall, T. Small balls U are arranged within these recesses, so that when the inner wheel turns in one direction the balls will be wedged between the wall T and the walls of the smaller ends of the wedge-shaped recesses, thus causing the outer wheel to rotate with the inner wheel. A reverse movement, however, brings the balls into the larger parts of the wedge-shaped recesses, and hence the outer wheel will not be driven by the movement of the inner wheel.

What I claim is—

1. The combination, with the treadle mechanism having the fulcrum-bar A at the front

of the machine, from which extend rearwardly the treadles connected by a vibratory beam, G, at the rear of the machine in lieu of the front, and a rod connecting the treadles with the driving-shaft, of the fly-wheel secured rigidly on the latter, and having pins R, and the fly-wheel carrying a spring-ring, N, adapted to turn within an annular channel, and having the wedge P, adapted to be engaged by the pins on the fly-wheel, substantially as and for the purpose herein shown and specified.

2. The combination, with the fulcrum-bar A at the front of the machine, of the treadles B, pivoted or having bearings thereon at their front ends, and extending rearwardly therefrom and connected by the vibratory beam G at the rear of the machine in lieu of the front, and the rod connecting one of the treadles

with the crank of the driving-shaft, substantially as and for the purpose specified.

3. The combination, with the fly-wheel rigid on the driving-shaft and having eccentrically-arranged pins R R, of the driving-wheel having a recess to receive a spring-ring, N, arranged to turn in a channel in said recess, and having a slot, O, to receive one end of a wedge, P, adapted to be engaged by the pins R R, as set forth.

In testimony that I claim the foregoing as my own I have hereto affixed my signature in presence of two witnesses.

THOMAS SKELDING TONGUE.
